UNITED STATES PATENT OFFICE

EMANUEL J. PERRY, OF NEW BEDFORD, MASSACHUSETTS, ASSIGNOR, BY MESNE ASSIGNMENTS, TO THE AMERICAN LAUNDRY MACHINERY COMPANY, OF NORWOOD, OHIO, A CORPORATION OF OHIO

WASHING MACHINE

Application filed August 13, 1925. Serial No. 50,076.

The invention relates to improvements in a motor driven washing and dyeing machine of the unloading cylinder type.

It is an object of this invention to provide a washing machine of the type wherein the washing cylinder is rotated in a casing for cleansing clothes contained therein and is then lifted from the casing to one side thereof so that the clean garments will drop from the container.

The invention has special reference to improved power mechanism for rotating the washing cylinder in alternate directions in the casing and for also lifting the cylinder from the casing.

In the accompanying drawings

Fig. 1 is an end elevation of the washing machine with the casing in its closed or washing position.

Fig. 2 is a transverse sectional view showing the manner of driving or rotating the washing cylinder.

Fig. 3 is a view of the opposite end of the device with the casing open and the washing cylinder in its unloading position.

Fig. 4 is a front elevation with the parts in the position shown in Fig. 3.

Fig. 5 is a rear elevation of the device.

Fig. 6 is an enlarged longitudinal sectional view showing the mechanism for rotating and swinging the washing cylinder.

Fig. 7 is a transverse sectional view on the line 7—7 of Fig. 6.

Fig. 8 is a plan view of the gear shifting mechanism.

Fig. 9 is an enlarged transverse sectional view of the brake mechanism of the washing cylinder, and

Fig. 10 is a longitudinal sectional view on the line 10—10 of Fig. 9.

Referring now more particularly to the drawings wherein like reference characters indicate corresponding parts, the numeral 1 designates the casing or housing of the washing machine having suitable side walls 2.

This casing is preferably provided with a movable door or closure 3 carrying segmental side sections 4, which closure is connected to the casing by suitable pivots 3a and capable of being moved to a position to permit the container within the washing machine to be lifted from the casing. The casing, of course, has the usual supporting legs and the usual water inlet and water outlet which are common in washing machines of this type.

Disposed within the casing 1 is the perforated washing cylinder 5 provided at each end with a spider 6 carrying trunnions 7 constituting the bearings for the washing cylinder. These trunnions seat within suitable bearings 8 formed in the side walls of the casing and it is upon these trunnions that the washing cylinder rotates. The spider furthermore has peripheral gears 9 constituting the driving gears for alternately rotating the washing cylinder in the casing. One spider is disposed at each side of the cylinder and is connected thereto by bolts or the like. It will be understood that the washing cylinder during a washing operation rotates in one direction, and then in another to most effectively wash garments contained therein. The present invention embodies a motor mechanism for imparting this rotary motion to the washing cylinder. This cylinder is rotated in the following manner:

Seated upon a motor support 10 is an electric motor 11. This motor is provided with the usual automatic controls so that it rotates in one direction a given period of time and then reverses and operates in another direction.

The motor drives an armature shaft 12, including a sliding coupling 12a, extending through a housing 13 and carries within the housing a driving gear 14. The shaft 12 then extends to a coupling 15 where it is loosely coupled with a control shaft 16 which will be more fully hereinafter described. The gear 14 in the housing 13 meshes with

one of a pair of gears 17 or 18. The gear 17 is the gear employed for operating or rotating the washing cylinder. The gear 18 is utilized for lifting the cylinder from the casing in a manner which will later appear. Assuming that the motor is operating due to the admission of current thereto, which current is controlled by the operation of the end lever 13' at one end of the machine, which lever carries a pair of extensions 14' beyond its pivot, each extension being adapted to engage a switch plug 15', one of said plugs being arranged so that when it is depressed the current is supplied to the motor and the other plug is arranged and constructed so that when it is depressed the supply of the current to the motor is discontinued. The motor, is, upon the operation of this lever, thrown into circuit with a source of electrical energy and the rotation of this motor rotates the shaft 12, gear 14, gear 17, which latter gear is keyed to the shaft 19 carrying at each end sprocket wheels 20. These sprocket wheels receive chains 21, which mesh with sprockets 22 keyed to the shaft 23 disposed at the rear of the machine and journaled in suitable bearing 24. The driving shaft 23 carries a pair of separated gears 25 mounted within suitable housings 26 projecting from the rear of the machine. These gears enter or pass through openings in the casing 1 and mesh with the peripheral gears 9 carried by the spider 6. Obviously the rotation of the shaft 23 imparts a rotary movement to the washing cylinder through the driving devices herein described. This cylinder is driven alternately in opposite directions, the motor having suitable controls which are well known in the art for reversing its direction of rotation at determined time intervals. Inasmuch as such mechanisms are so well known in the art it is not deemed necessary to disclose this control in detail. It will be understood that as long as the handle 13' is coacting with the starting switch this rotary movement of the container 1 continues. When it is desired, however, to remove the clothes from this container the rotation of the container must cease, but in order that the container may be elevated or lifted from the casing 1, prior to lifting this container it is desirable to lock the same against rotation and in a position where the door opening in the container is directed toward the floor of the laundry or the like. I have described this braking mechanism in detail in my co-pending application Serial No. 50,075, but the same will be briefly referred to herein.

One of the trunnions 7 of the container is received in a housing 27 having disposed therein a brake drum 28, which drum is keyed to said trunnion 7. A brake band 29 is disposed around this drum, said band being mounted at one end on a support 30 while

its other end is formed with a loop 31 in which there is provided an eccentric or cam 32. The cam is mounted on a shaft 33 which extends through the housing 27 and obviously when this cam is rotated it applies or removes the brake band from contact with the drum. It is essential that the application of the brake be so timed that the container will be stopped in its motion at a position where the discharge opening therein directly overlies the floor of the laundry so that the garments will fall through this discharge opening. With this in mind the trunnion 7 carries a brake operating element 34, the periphery of this element engaging a roller 35 on an operating arm 36 which carries a dog face 37. The shaft 33 also carries a dog 38 which is keyed to this shaft so that when the dog face 37 is brought into contact with the dog 38 and the trunnion 7 is rotating this trunnion due to the eccentrically mounted element 34 will shift the arm 36 and in so shifting this arm will, of course, oscillate the shaft 33 which in turn oscillates the eccentric 32. To throw the dog face 37 into contact with the dog 38 a hand lever 39 is provided which rides in an inclined slot 39' in the casing 27 and obviously as this lever is moved in this slot it causes the dog face 37 to move toward and in contact with the dog 38. Just prior to the stopping of the rotation of the washing cylinder 5 this lever 39 is shifted to effect this connection of the dog and then as the container rotates the roller 35 on the arm 36 coacts with the element 34 and this arm is swung outwardly by this element 34 to turn the cam 32 and apply the brake. The parts are so positioned that the brake is only applied when the door opening A of the container will occupy a position facing the floor of the laundry when ejected from the casing by the raising and lowering mechanism to be now described.

Referring to Figs. 1, 9 and 10, it will be observed that the brake operating shaft 33 has rigidly secured thereto a crank arm 66 which in turn is connected with lever 13' by means of an adjustable link 65. Thus it is apparent that when the shaft 33 is actuated by movement of the cylinder to apply the brake, the lever 13 will be operated through link 65 and crank arm 66 and consequently the driving motor will be deenergized. The lever 13' may be retained in shifted position by a detent mechanism if desired and accordingly I have illustrated in Fig. 1 of the drawings a conventional form of toothed segment positioned adjacent the lever and with which any suitable form of detent carried by the lever may be employed.

It will be understood that before the raising and lowering mechanism is placed in operation the rotation of the container or washing cylinder has ceased and said cylinder has also been locked against further movement.

It will be observed that the washing cylinder is supported in segments 40, one of these segments being disposed at each side of the machine. The trunnions 7 of the washing cylinder are mounted directly on arms of these segments. The segments are furthermore pivoted at 41 to the side walls of the machine and each segment at its periphery is provided with teeth 40'. These segments constitute the elevating and supporting means for the washing cylinder and when raised lift this cylinder from the casing. To so lift the cylinder from the casing the operator first shifts the handle 43 which is connected with a link 44 to a crank 45, which crank is connected to a gear shifter 46. This shifter is mounted in bearings 47. It will be understood that the shaft 12 and the shaft 16 are capable of a sliding movement for the purpose of coupling the gear 14 with either the gear 17 or the gear 18. While the shaft 12 rotates, the shaft 16 has no such movement, the connection 15 permitting the rotating and non-rotating shaft to be coupled without imparting the rotation from one shaft to the other. A shifter device 48 is mounted on a bracket connected with the machine and this device has a cam way 49 therein receiving a pin 50 fixedly attached to the shaft 16. When the operating lever 43 is shifted the rocking movement imparted to the shaft 16 is converted into a reciprocating movement by reason of the cam way just described, which movement shifts the shaft 12 with its gear 14 into mesh with the gear 18. This gear is rigidly attached to a sleeve 51 loosely turning on the shaft 19, the sleeve carrying a bevelled gear 52 which meshes with a gear 53 on the shaft 54, which in turn carries a spiral gear 55 that meshes with a gear 56 on the transverse shaft 23' extending across the back of the machine. This shaft 23' carries at each end gears 58 which mesh with intermediate gears 59 suitably journaled in a housing 60 and which intermediate gears in turn mesh with the gear teeth 40' on the washing cylinder lifting segments. If the push button 61 is then engaged current will be supplied to the driving motor and through the connections herein described the lifting segments will be raised from the casing carrying with them the washing cylinder. I also provide the push button 62 to manually cut off the current of the motor. To return the cylinder to the casing the push button 63 is operated, which through a suitable reversing control for the electric motor causes the rotation of the driving mechanism in a reversing direction, which returns the washing cylinder to the casing. When it is so returned current to the motor is cut off by the push button 62 and the lever 43 shifted to disengage the gear 14 from the gear 18 by reason of the movement of the shafts 12 and 16. The rotation control lever 13' is then shifted, it being observed

that this lever has a link connection 65 with an arm 66 connected with the brake operating cam shaft 33. The movement of this lever releases the brake while a further movement thereof causes the enlarged end 14' to engage the proper switch plug 15' to again rotate the cylinder in the casing, it being understood that after the cylinder is placed in the casing the casing door is moved to a closed position and, of course, the motor driving gear 14 moved into mesh with the cylinder operating gear 17.

Having thus described my invention, what I claim is:

1. In a washing machine, the combination with a casing, of a washing cylinder therein, a driving motor for rotating said cylinder, gearing interposed between the cylinder and the driving motor including a shiftable driving gear driven by said motor, elevating mechanism for lifting the cylinder from the casing, gearing for operating said mechanism, and manual means for shifting said shiftable gear into operative association with said elevating gearing for transmitting power from said motor to said elevating mechanism.

2. In a washing machine, the combination with a casing, of a washing cylinder therein, means for rotating said cylinder comprising a gear connected therewith, a driven shaft, a gear on said shaft meshing with the gear connected with said washing cylinder, means for rotating said driven shaft including a motor, a gear driven thereby operatively associated with said driven shaft, a lifting mechanism for raising said washing cylinder from the casing, and means for shifting said third mentioned gear into operative relation with said lifting mechanism to raise said cylinder.

3. In a washing machine, the combination with a casing, of a washing cylinder rotatable therein, a gear connected with said cylinder, a shaft, a gear thereon meshing with said gear on said cylinder, a driven shaft, driving connections between said shafts, an electric motor, a shiftable driving gear on the shaft of said motor for rotating said driven shaft, means for elevating the cylinder from said casing, and manually operable means for shifting said gear into operative association with said elevating mechanism, substantially as described.

4. In a washing machine, the combination with a casing, of a rotating cylinder therein, means for rotating said cylinder including a motor, a shaft driven thereby, a shiftable gear carried by said shaft, elevating mechanism for lifting said cylinder from said casing, and means for shifting said gear to engage either the driving mechanism for the cylinder or the elevating mechanism therefor.

5. In a washing machine, the combination

with a casing, of a rotating cylinder therein, means for rotating said cylinder including a motor, a shaft driven thereby, a shiftable gear carried by said shaft, elevating mechanism for lifting said cylinder from said casing, and means for shifting said gear to engage either the driving mechanism for the cylinder or the elevating mechanism therefor, said means comprising a manually operated lever, a shifter rod, and a guide having a cam way therein cooperating with said shifter rod to impart to said driving gear a rectilinear movement.

6. In a washing machine, the combination 15 with a casing, and a rotating cylinder therein, of a driving motor for rotating said cylinder, means for supporting the cylinder in said casing for enabling the same to be moved beyond the casing, elevating mechanism for 20 moving said cylinder, and a shiftable driving element driven by said motor for operating either the rotating means for the cylinder or the elevating mechanism therefor.

7. In a washing machine, the combination 25 with a casing, a cylinder therein, a gear rotatable with the cylinder, elevating members connected to the cylinder, and transmission mechanism for driving said gear and elevating members, said mechanism comprising 30 a support, a motor mounted on said support, a shaft directly connected with the motor, a second shaft journalled in said support, a pair of gears on said second shaft, a gear on the motor connected shaft, means for selectively meshing said last mentioned gear with either of said pair of gears, connections from one gear of said pair of gears to said cylinder gear, and connections from the other gear of said pair of gears to the elevating 35 members.

8. In a washing machine of the rotary cylinder, self-unloading type, the combination 45 with the washing machine casing and cylinder, of transmission mechanism supported by the casing for both rotating and elevating said cylinder, said mechanism comprising a power shaft, a gear train for rotating said cylinder, a second gear train for elevating said cylinder, and means including a driving 50 element common to both gear trains and operable to connect said trains separately to said power shaft.

9. In a washing machine of the rotary cylinder, self-unloading type, the combination 55 with the washing machine casing and cylinder, of power means, a train of mechanical elements for rotating the cylinder, a second train of mechanical elements for elevating the cylinder, means for selectively 60 connecting both of said trains to the power means, and a manually operable device for setting said connecting means to cause either one of said trains to be driven by the power means.

65 10. In a washing machine, the combina-

tion with a casing and a cylinder, of a gear connected with the cylinder for rotating the latter, a member connected to the cylinder for elevating the latter, a power shaft, a gear train for operating the cylinder connected gear, a second gear train for operating the cylinder elevating member, and means including a driving element common to both gear trains and operable to connect said trains separately to said power shaft.

In testimony whereof I affix my signature.

EMANUEL J. PERRY.
